MACHINE FOR PACKAGING WIRE FORMS

William F. Feyrer, Englewood, N. J., assignor to
Nathan L. Solomon, Englewood, N. J.

Application July 18, 1945, Serial No. 605,680

21 Claims. (Cl. 140—87)

1

This invention relates to machines for shaping, processing and packaging wire-forms. More particularly, the invention deals with machines of this type and kind wherein wire-forms are grouped and counted at a packaging station, and a packaging element, such for example as a card, is delivered to the station for arrangement of the wire-forms thereon in predetermined arrangement, and then the packaged or mounted forms discharged from the machine. Still more particularly, the invention deals with machines of the class described, wherein a single source of power is employed for actuating the several mechanisms of the machine. The novel features of the invention will be best understood from the following description when taken together with the accompanying drawings, in which certain embodiments of the invention are disclosed, and in which the separate parts are designated by suitable reference characters in each of the views, and in which:

Fig. 1 is a plan view diagrammatically illustrating the complete machine assemblage.

Fig. 2 is a side view diagrammatically illustrating the machine, as shown in Fig. 1.

Fig. 3 is a wiring diagram of the machine shown in Figs. 1 and 2.

Fig. 4 is a fragmentary end view diagrammatically showing the stripper mechanism and drive arrangement, the section being taken on the line 4—4 of Figs. 1 and 2.

Fig. 5 is a sectional view of the outlet side of the loading mechanism taken on the lines 5—5 of Figs. 1, 2, 7 and 29, showing diagrammatically, the product holder platen in three different positions in full lines, with the lever for actuating the same shown in part in dot and dash lines in two positions, and in full lines in the third position.

Fig. 6 is an enlarged detail view of the main slide and platen of Fig. 5, showing the platen in the top lifted and holder position, with part of the construction broken away and in section, the view being taken from the opposite side of the showing in Fig. 5.

Fig. 7 is an end and sectional view of the main slide and platen assembly, shown in Figs. 5 and 6, as viewed in the direction of the arrows 7—7 of Figs. 5 and 6.

Fig. 8 is a fragmentary cross sectional detail, a main slide detent taken on the line 8—8 of Fig. 6.

Fig. 9 is a plan view of the hopper of the machine, with parts of the construction broken away and in section.

2

Fig. 10 is a side and sectional view of the hopper shown in Fig. 9, with parts of the construction broken away and in section, and illustrating the removal of the lowermost product or card of the stack from the hopper.

Fig. 11 is a fragmentary end view of the hopper as viewed in the direction of the arrow 11—11 of Fig. 10, part of the construction being shown in section.

Fig. 12 is an end view of the hopper and platen, as viewed in the direction of the arrow 12—12 of Fig. 10.

Fig. 13 is a fragmentary plan view of the holder as shown in Fig. 15, with part of the construction broken away and in section.

Fig. 14 is a side view of that part of the machine shown in Fig. 15, with part of the construction broken away.

Fig. 15 is an end view of the structure shown in Fig. 14, part in section, the section being on the line 15—15 of Fig. 14.

Fig. 16 is a partial section on the line 16—16 of Fig. 18, showing the operation of loading or mounting the products.

Fig. 17 is a fragmentary view similar to Fig. 16, showing the parts in a different position.

Fig. 18 is an end and sectional view substantially on the line 18—18 of Fig. 14.

Fig. 19 is a top plan view of the counting and staggering mechanism of the machine.

Fig. 20 is a fragmentary sectional view of the part of the mechanism shown in Fig. 19 on the line 20 of said figure.

Fig. 21 is a side view of the counting and staggering mechanism shown in Fig. 19.

Fig. 22 is an end view of the counting and staggering mechanism shown in Figs. 19 and 21.

Fig. 23 is an elevation and sectional detail view, on an enlarged scale, showing the driving connection between the main drive and the packaging mechanism, and disclosing the set stop clutch employed.

Fig. 24 is a partial section on the line 24—24 of Fig. 23.

Fig. 25 is a fragmentary sectional view taken on the line 25—25 of Fig. 24.

Fig. 26 is an end view of a band, guiding and cam setting mechanism with part of the construction broken away and in section.

Fig. 27 is a side view of the mechanism shown in Fig. 26, the view being taken on the line 27—27 of Fig. 26, with parts of the construction broken away and in section.

Fig. 28 is a view similar to Fig. 26, showing

only a part of the construction and with parts in a different position.

Fig. 29 is a plan view of the product counting and staggering mechanism, the product loading and dispersing mechanism, the hopper, product ejecting mechanism, and other associated parts of the machine.

Fig. 30 is a diagrammatic plan view of a modified form of counting, grouping and staggering mechanism.

Fig. 31 is a fragmentary end view of the counting mechanism shown in Fig. 30.

Fig. 32 is a side view of the counting mechanism shown in Fig. 31.

Fig. 33 is an end view of the modified grouping mechanism shown in Fig. 30.

Fig. 34 is a side view of the grouping mechanism shown in Fig. 33.

Fig. 35 is a fragmentary end view of the modified staggering mechanism shown in Fig. 30.

Fig. 36 is a plan view substantially of the framework of the grouping and mounting mechanism of the machine, omitting most of the works in order to clearly illustrate the frame.

Fig. 37 is a side view of the structure as seen in Fig. 36, with parts of the construction broken away and in section; and

Fig. 38 is an end view of a part of the structure shown in Fig. 36, looking at the right-hand end of the frame.

My present invention deals with a machine which first forms and then processes wire-forms, such for example as bobby-pins, these steps of forming and processing being disclosed in the application of Jean R. Taplinger, Ser. No. 540,732, filed June 16, 1944, now Patent No. 2,589,518, issued March 18, 1952, and further to the counting, grouping and staggering of the products or wire-forms preparatory to packaging these forms or to mounting the staggered groups upon a mounting card in staggered relationship to each other, and finally to automatically eject the packaged or carded products from the machine.

In view of the fact that the forming and processing mechanism of the machine, from a specific standpoint is the subject of a separate application, this part of the machine is only diagrammatically illustrated in Figs. 1 to 4 inclusive, except insofar as showing the modification of employing a single drive for all of the mechanisms of the machine. Further means is provided to pass wire-forms or other products freely through what I will term "the packaging and dispensing unit" of the machine for discharge from the band or conveyor substantially in accordance with the teachings in the application herein identified.

Briefly stated, it may be said that the machine first produces a series of shaped and processed products arranged and spaced on a conveyor band, then to count and segregate predetermined quantities of said product on the band to form groups of said products, then in counting and segregating the groups, and further in staggering said groups one with respect to the other, then in packaging or carding the staggered groups, and finally in ejecting the package or card from the machine.

In Figs. 1 and 2 of the drawing, 50 represents an endless band or conveyor, which passes around spaced pulleys 51 and 52 arranged in the spaced relation shown, and driven from one power source or drive, for example, an electric motor, as at 53, through an elongated drive shaft 54 suitably supported and having bevelled

gear drives to the pulley shafts, as at 55 and 56.

At 57 is shown the machine for producing wire-forms, such for example, as bobby-pins, in accordance with the teachings in the application hereinbefore cited. The band 50 passes through the machine 57, as taught in said application, through a tempering oven 58, guide discs 59, under the nozzle 60 of a coating mechanism to coat the products or wire-forms, then under the nozzles 61 of a blower mechanism to remove surplus coatings, then through a baking oven 62, and then through the packaging apparatus or unit 63. This last unit is illustrated in detail throughout the accompanying drawings, and is diagrammatically shown in Figs. 1 and 2 of the drawing. After passing through the unit 63, the band passes through a stripper mechanism 64 for the purpose of stripping or removing the wire-forms from the band when such forms are permitted to pass freely through the unit 63. The stripper mechanism is of the type disclosed in the application hereinbefore referred to, and is driven from the drive shaft 54 through a take-off on the shaft of the pulley 52, as generally indicated by the reference character 65 in Fig. 1 of the drawing. The stripper mechanism simply comprises two spring pressed rollers designated by the reference character 66 in Fig. 4 of the drawing driven through belt and pulley mechanisms, as shown in Fig. 4, to engage and strip the wire-forms from the band, should such wire forms prevail thereon.

The motor 53 is located adjacent the forming machine 57, and has a take-off chain and sprocket construction 67 onto a shaft 68, geared to the shaft 54 through the intermeshing bevel gears at 69. Also geared to the shaft 68 as at 70, is a supplemental elongated drive shaft 71, for driving the shaft 72 of the packaging unit 63 through the intermeshing gears 73 and 74.

The sprayer and blower mechanisms are driven from the shaft 54 by gears 75 through a speed-up gear box 76 and other associated drives, as indicated diagrammatically in Fig. 1. From the foregoing, it will appear that the entire machine operates from the single source of power drive, and the forming machine 57 may be operated through a sliding dog-tooth clutch as at 77.

Before proceeding to describe the packaging and dispensing unit, it would be well to refer to the diagrammatic showing of the electrical wiring diagram in Fig. 3 of the drawing. In said figure, the source of supply is controlled by a switch 78, and 79 represents the resistance of the oven 58; 80 the resistance of the baking oven 62; 81 a resistance for softening the coating material on the band prior to scraping the material therefrom by scrapers diagrammatically illustrated at 82 in Fig. 2 of the drawing.

In the diagram, the electric motor 53 is in circuit with the source of supply through the wires 53', and controlled by a switch 53''. The illustrations in full lines in Fig. 3 is an electrical diagram for the unit machine shown in Figs. 1 and 2. It will be apparent, however, that in some instances, it will be desirable to provide independent drives for the sprayer and blower mechanisms, as well as the band, feed and stripper mechanism, and in such instances, separate motors, as indicated in dotted lines at 53a and 53b will be employed, and in circuit with the source of electric supply, more or less in accordance with the teachings in the application hereinbefore referred to, where separate motors are employed to actuate different mechanisms

of the machine. It will further be apparent that a separate drive may also be provided for the packaging mechanism. However, it is desirable that a definite synchronism of operation be provided between the forming mechanism and packaging mechanism.

Counting, dispersing and packaging unit

This unit may be more generally classified as a packaging or carding unit. This unit comprises a main frame 83, note Figs. 36 and 37, the frame being more or less box-shaped in form, and in this frame is suitably supported the shaft 72 having its drive gear 74 meshing with the pinion or gear 73 on the shaft 71. The gear 74 is free to rotate on the shaft 72, and is engaged with the shaft through a clutch 84, which is shown in detail in Figs. 23 to 25 inclusive. This clutch comprises a longitudinally sliding disc 85 and a pin 86 thereon, adapted to mesh with a pin 87 embedded in the hub of the gear 74. When said pair of pins are adjacent each other, as shown in Fig. 23, rotation of the gear 74 by the gear 73 causes the sliding disc, through the key 88, to effect positive rotation of the drive shaft 72. However, when said pins are disengaged relative to each other, as shown in Fig. 25, the large gear can no longer effect said rotation of the drive shaft. A plurality of springs 89 normally urges the slide disc 85 toward the large gear 74, as may be appreciated, viewing Fig. 23, said springs being partially supported in suitable sockets in the disc 85 and in a hand wheel 90, secured to the main shaft. Connection and disconnection of the clutch is effected by a plunger 91 being shifted into the lowered position shown in Figs. 23 and 24 by a hand operated lever 92 pivoted to the frame 83 as seen at 93, note Fig. 36, said lever having a rounded end 94 entering a slot 95 in said plunger. Supported in connection with the frame is a spring detent 96, note Fig. 23, adapted to enter the groove 97 of the plunger 91, in order to maintain the latter in the lowered position shown in Figs. 23 and 24, and adapted to enter the groove 98 of the plunger to maintain the latter in a raised position shown in Fig. 25. When this plunger is in the lowered position of Figs. 23 and 24, springs 89 force the sliding disc 85 toward the front of the carding machine and thereby move the pin 86 fully into the path of the pin 87 on the large gear 74, to effect rotation of the main shaft 72.

It will be apparent, that when the plunger is in the raised position, it is brought into alignment with the cam surface 99 of the disc 85, thus causing the disc to move to the left against the action of the springs 89, preventing clutching engagement through the pins 86 and 87 and allowing the gear 74 to rotate freely on the shaft. The actuation of the lever 92 will be later described.

Counting Mechanism

A counting mechanism 100, note Fig. 1, and best seen in Figs. 19 through 22 inclusive, and 29, includes a cam 101 suitably secured to the main shaft 72, adapted to vertically reciprocate a counter-slide 102 in a suitable channel 103 of a top cross-bar 104, being held in said channel by a plate 105. A head 106 is suitably secured to the top of the counter-slide and is provided with a dove-tailed channel 107 adapted to accommodate a dove-tailed slide 108 for movement longitudinally of the carding machine, as by the screw 109, note Fig. 21. This dove-tailed slide

has a channel 110, the bottom of which is slightly beyond the outer face 111 of the head 106, whereby the counter-finger 112 may be locked in the channel, as by the screw 113, and yet permit longitudinal movement of said dove-tailed slide and finger 112 without interference by the head 106. The stop finger is provided with an elongated slot 114 to permit initial vertical setting thereof, note Fig. 21.

A suitable hardened finger 115 is secured in a suitable socket 116 at the lower end of the counter-slide 102 and is adapted to engage with the periphery of the cam 101. It will appear from a consideration of Fig. 22, that the cam has three active surfaces or lobes operating upon the finger 115 to raise the slide 102 three times upon each revolution of the shaft 72. The gear ratio provided between the unit 63 and the forming machine 57 is such that the shaft 72 rotates once for each eighteen revolutions of the forming machine 57, thus causing the cam 101 to segregate eighteen pieces of the product on the band 50 into three groups of six. It will here be understood that other segregations and groupings may be provided by appropriately controlling the ratio of drive and the types of cams employed. That is to say, the number of products in each group and the number of groups may be determined.

The adjustment of the screw 109 is to arrange the finger 112 in the desired position with respect to the products on the band, viz., the points 117 of the finger 112 should raise immediately in back of the last piece of product in a group, so that a minimum of space is provided between said group and the next or lead piece of the product for the succeeding group. This part of the unit 63 serves to effect an initial counting, grouping and dispensing of the product which is to be carded.

Considering Fig. 22, it will appear that the points 117 of the finger 112 are adapted to straddle the band 50 in engaging a product or wire-form, such for example as the bobby-pin 118 illustrated in said figure in the grouping of the products, as later described.

Staggering mechanism

Preferably the groups of products, see groups 118a, 118b and 118c in Fig. 29, are staggered relatively to each other and transversely relative to the band 50, to have a better appearance on the product holder or card, and to have slots offset somewhat on the card to lessen the likelihood of the card creasing or breaking. To this end, the present invention provides a novel staggering apparatus including a pair of slides 119 and 119' adapted to reciprocate transversely of the machine in a channel 120 wherein they are retained by plates 121, said reciprocation being effected by arms 122 and 122', note Fig. 22, having sliding pivotal couplings with slides 119 and 119', as at 122" and suitably pivoted at 123 and 123'. The slides 119 and 119' are provided with primary heads 124 and 124' respectively. The heads move vertically in channels 125 and 125' of the slides, and a suitable setting is achieved by elongated slots 126 and 126' and set screws 127 and 127', note Fig. 22.

Secondary head units 128 and 128' comprise two parts adjustable relatively to each other and to the heads 124 and 124', by dove-tailed portions 129 and 129', 130 and 130', note Fig. 22. These supplemental heads or the dove-tailed portions 130 and 130' thereof, control the relative posi-

tioning of flanged staggering blocks 131 and 131' with respect to the products 118 in the movement of the groups of products into staggered relationship with respect to each other. It will be apparent that one of the groups of products may be centralized in the machine, whereas the other groups may be staggered one to the right and the other to the left. In order to effect this operation, I provide a disc 132, note Fig. 22, having a plurality of adjustable cam lobes 133 on one side of the disc and a plurality of similar lobes 134 on the other side thereof. The lever 122 carries a roller 135 arranged to operate on the cam lobes 133, and the lever 122' carries a roller 135' adapted to operate upon the cam lobes 134. When all of the cam lobes are set in an intermediate position, the entire mechanism would function to centralize all groups of the products transversely with respect to the band 50. However, when a cam lobe set low engages with the roller of one lever, and the opposed lever engages concurrently a cam lobe set high, the products will be moved either to the left or to the right. The spring 135" supports rollers 135 and 135' in engaging the disc 132 and the cam lobes. 25

Considering Fig. 22, it will appear that two opposed cam lobes 133 and 134 have a common setting, whereas the other two opposed pairs have high and low settings which provide in the cycle of operation of the machine the staggered relationship of the groups of products shown at 118a, 118b and 118c in Fig. 29.

Modified counting and staggering mechanism

In Figs. 30 to 35 inclusive, I have illustrated a modified and simplified form of counting, staggering and dispersing mechanism comprising a counter mechanism, Figs. 30, 31 and 32, including a counter-finger 136 reciprocated vertically relative to a band 137 by a slide 138 and a cam 139 similar to the counter mechanism hereinbefore described in detail. The slide 138 is of sufficient weight to normally drop by gravity into engagement with the cam 139 and to ride the irregular surface thereof. However, this modified form of counting and staggering mechanism differs from the form hereinbefore described, at least in one important respect, by providing a unitary multi-grouping mechanism including a vertically reciprocable slide 140 carrying a plurality of fingers 141, 141' and 141" settable into divers longitudinal and vertical positions through the media of dove-tailed blocks 142, 143 and 144 respectively. The dove-tailed blocks are slideable longitudinally in a single channel 145 and are locked in the desired longitudinal position concurrently with locking of said fingers in vertical position by block clamping screws 146 operating in elongated slots 147, as clearly seen in Fig. 34. By viewing Figs. 30 and 34, particularly it will be appreciated that the cam lobe 148 lifts the finger 141" into a position to intercept a lead group of product and to maintain the same in the position 149 of Fig. 30 while the band continues traveling while lobe 150 through the further rotation of the cam moves the finger 141' up into position to intercept a second group of product 149', and thereafter, lobe 151 lifts the lowest finger 141 up into position to intercept a third group of product 149" while the band continues to travel, whereupon slide 140 drops down into engagement with the lowermost lobe 152, and all three fingers are cleared with respect to the band 50a and the groups 149, 149' and 149" which they just collated upon the band. This low lobe 152

on the cam is of sufficient length to maintain the fingers in the clear position with respect to the band until the just collated three sets are entirely clear of the three fingers and the next succeeding lead group is closely approaching finger 141", whereupon the latter is again lifted up into intercepting position. Now, it should also be particularly noted, that the multi-grouping mechanism just described in detail, serves the function of accurately spacing the groups longitudinally of the band concurrently relative to each other, as may be seen by observing the spacing between both sets of three groups shown in Fig. 30, and between the end set of grouped product in the multi-grouping apparatus and the succeeding set just made up by the counting mechanism, viz., serves to close in the spacing between the groups made up by the counting mechanism.

Staggering of the groups of product is effected by the mechanism as shown in Fig. 30 and 35 and includes a pair of levers 153 and 153' pivoted, as seen at 154 and 154', said levers having rollers 155 and 155' respectively at the lower end thereof adapted to be maintained in constant rolling contact with the cam 156, as by a spring 157. These levers 153 and 153' are provided with multi-station staggering blocks 158 and 158' at the upper end thereof. Staggering block 158 is provided with a plurality of faces 159, 159' and 159", while the mating staggering block 158' is provided with a plurality of matching faces 160, 160' and 160", note Fig. 30, adapted to move the three groups of product of the multi-grouping mechanism station into staggering position transversely relative to the band, as shown by the three groups, in the leaving position, as shown at the right hand side of Fig. 30. Arcuate movement of levers 153 and 153' with associated staggering blocks 158 and 158' respectively, from the inoperative position shown in Fig. 35 into a top closed position to work on opposite ends of grouped product and to effect a staggering thereof, is accomplished by lobes 161 and 161' engaging the rollers 155 and 155'. The staggering mechanism is operated briefly just as the third or final group 149" assumes its position adjacent the finger 141. This modified form of counting, grouping and dispersing apparatus of Figs. 30 to 35 inclusive, may be used in lieu of the counting, grouping and staggering mechanism of Figs. 19 through 22 inclusive.

Loading apparatus

The loading apparatus of the unit 63 may be seen best in Figs. 13 through 18 inclusive, in Fig. 29, plus slight fragmentary showings thereof in Figs. 5 through 8 inclusive. This mechanism is supported in a suitable box 162 including side walls 163 and 164. End walls 165 and 166 of the box 162 are each provided with three slots, as noted in Fig. 29, adapted to support stop plates 167, 167' and 167" for vertical movement within the box 162, said stop plates being provided with slots 168 at the bottom thereof, note Figs. 14, 16 and 17, adapted to envelope the band 59, and thereby effectively stop groups of product carried by the band underneath the box 162. Vertical movement of said stop slides is controlled by the cams 169, 169' and 169" respectively upon the shaft 170, this shaft in turn being rotated in unison with the main shaft 72, as by the sprocket drive 171, note Figs. 5, 15 and 29. This drive is arranged to effect a concurrent one to one rotation of shafts 170 and 72.

The cams are suitably shaped to successively drop the stop plates into the path of incoming groups of product and to lift them clear of, or above the band at a predetermined point in the cycle of the machine. Fig. 18, for example, discloses lowpoints of cams 169' and 169'' in engagement with the pins 172' and 172'' of the stop slides 167' and 167'', whereby stop slide 167'' maintains group X against movement with the band 50, and whereby the stop slide 167' is in position to stop further movement of the group X-2 with the band while a higher lobe section of the cam 169 is still in engagement with the pin 172 of the stop slide 167 to maintain the latter in the raised position until the group X-2 is fully clear of the under section thereof and into engagement with the stop slide 167', whereupon a drop section in the cam 169 permits it to quickly move vertically by gravity into intercepting position with respect to the band and thereby stop group X-3 against further travel with the band for a predetermined length of time.

It will be understood that in the operation of the mechanism shown in Fig. 18, all the plates are normally in raised position and then one plate, for example, the plate 167'' drops downwardly to check the group X, the other plates being raised to clear the group X as it advances with the band. The plate 167' then drops, stopping the group X-2, and so forth.

Staggering and backing mechanism

In order to effectively stagger, or laterally disperse groups of product on the band, the present invention provides a novel staggering and backing mechanism, including a bell crank 173 having a roller 174 at its upper end, maintained by a spring 175 in constant engagement with a cam 176 secured to the shaft 170. At its lower end, said bell crank is provided with a link connection 177 to a lever 178 secured to a secondary shaft 179, said secondary shaft in turn being provided with a plurality of staggering and backing fingers 180, 180' and 180'' adjacent the stop plates, as seen in Fig. 18. The operative face of the cam 176 is developed so that the associated mechanism through the shaft 179 preferably concurrently moves all three staggering and backing fingers from the retracted position shown in Figs. 17 and 18, into the operative position of Fig. 16. Each of said fingers 180, 180' and 180'' is provided with inner backing faces, such as the face 180a, Fig. 16, but preferably in slightly different arcuate planes to effect and coincide with the staggered relationship of the groups 118a, 118b and 118c, when all three fingers are moved into the operative position of Fig. 16, as will be readily appreciated. The desired arcuate position is achieved as by a set screw connection 181 shown in Figs. 16 and 17. The faces 180a of the fingers are adapted to overlie the upper surfaces of the groups of product to limit upward movement thereof. These faces serve very effectively to back up groups of pins as a card 182, note Fig. 16, is forced into the grouped product in a manner shortly to be described.

Pressing Mechanism

The box 162 also supports a pressing mechanism, including a slide 183 having a vertical section fitting into suitable channels 184 and 185 in side walls 163 and 164, note Fig. 29, normally held in the raised position as by the springs 186 and 186', note Fig. 15, connected at their upper hooked ends to studs 187 and 187', and at their

lower ends to links 188 and 188', said links in turn being connected to the slide 183 as at 189, note Fig. 16, and at their forward end to side walls 163 and 164 as by the studs 190 and 190', note Fig. 18. The pressing slide 183 is provided with a plurality of slots 191, note Fig. 13, receiving pivot pin ends of three fingers 192, 192' and 192'', as may be seen best in Figs. 13, and 16. The finger 192'' is shown in section in Fig. 16. These fingers are normally urged downwardly, as viewed in Fig. 16, by springs 193, adjusted and backed by studs 194, said downward movement being limited by adjustable screws 195. Normally the pressing slide and fingers are in a raised inoperative position until all groups of pins are properly grouped by the stop slides, and also staggered and backed by the backing fingers, whereupon cams 196 and 196', on shaft 170, see Figs. 14, 16 and 18, particularly during rotation of shaft 170 engage links 188 and 188' to move the slide 183 into the lowered position of Fig. 16, and thereby press fingers 192, 192' and 192'' into overlying engagement with the upper ends of grouped product to move and advantageously control open ends of said grouped product when the latter is loaded onto a card or the like. Retraction of said pressing slide and associated pressing fingers from the advanced or operative position of Fig. 16 into the inoperative position of Fig. 17 is preferably effected concurrently with the lifting of stop slides and retraction of staggering and backing fingers to their inoperative positions.

As a safety precaution, I provide a cam 197, note Figs. 15, 16 and 18, to concurrently lift all of said stop plates 167, 167' and 167'' into a raised inoperative position and to maintain the same in said raised position even though the cams 169, 169' and 169'' would normally allow them otherwise to drop, said cam 197 extends between the side walls and pivoted therein with a pin 198 which in turn has a handle 199 for manually rotating the same. The cam 197 operates in a rectangular cutout 200 in each of the slides or stop plates, and is adapted to engage the top walls of said cutouts. Thus, when the cam 197 is moved from the lowered position note Fig. 16 in a counter-clockwise direction 180 to 200°, it simultaneously lifts all three stop plates an appreciable extent and fully clear above the band and groups of product carried by the band, to allow free passage of product to the stripper 64 of Figs. 1 and 2.

Card controlling apparatus

A novel hopper 201 is provided by the present invention to store a large quantity of product holders such as the card 182 or the like for use in the machine, and to facilitate automatic removal of cards, one at a time, from the point of storage to points of loading and expulsion. The hopper 201 in its present preferred form, includes a box with side walls 202 and 202' having channels for longitudinally locating and slidably supporting end plates 203 and 203' respectively, said two walls and end plates being of a configuration and location to easily accommodate and guide a stack of superposed cards. Plates 203 and 203' are secured in said vertical channels, as by screws 204, with suitable elongated slots 205 permitting desired vertical setting of the end plates with respect to the side walls. To facilitate minute adjustments of said end plates 203 and 203', the latter are provided with screws 206 overlying the side. Thus to accu-

11

rately drop the end plates a few thousandths of an inch, it is merely necessary to loosen said screws the desired extent, using a feeler gauge underneath the screws, then loosening the side screws 204 until the end plate drops into the lowered position permitted by the adjusting screws, and conversely by rotating the screws in the opposite direction after loosening the side screws, it is possible to accurately lift the end plates the desired extent. The side walls rest directly upon the top faces of the rails 207 and 207', note Fig. 12, at which point they are secured to holding bars 208 and 208' respectively, with the latter thoroughly secured to the rails as by screws 209 fastened through elongated slots 210 and thence threaded into rails 207 and 207' while connection of side walls 202 and 202' to said holding bars is effected by screws 211 and 211' extending through elongated slots 212 and 212', in said bars, note Figs. 9 and 10. This construction provides location of the hopper 201 in various positions longitudinally of the rails. To prevent the hopper from shifting transversely relative to the rails, the end walls are preferably made of just the same width as the space between the rails 207 and 207'.

A plurality of L-shaped fingers 213, 213' and 213'', note Figs. 10 and 12, having vertical sections fitting in suitable slots in the wall 203 of the hopper (Figs. 9, 10 and 11) and longitudinal sections extending across the bottom of the hopper (Figs. 9, 10 and 12) serve to prevent cards from dropping out of the bottom of the hopper. These fingers are secured to the rear plate as by screws 214 while elongated slots therein permit relative vertical fitting of fingers. The longitudinal sections thereof are preferably made long enough to extend under the front end plate 203' and at this point form an outlet opening, as seen at 215, Fig. 10 of the drawing, equivalent to the thickness of one card 182, and thereby provide an outlet port for only one card at a time. Accurate setting of this port is achieved with the screws 206 at the upper end of rear and front plates in the manner hereinbefore described.

Signal

In order to apprise the operator when the stack of cards in the hopper is getting low, the present invention provides a relatively simple signal including a spring arm 216 mounted upon and insulated from the side wall 202' upon insulation block 217. This spring arm has one finger 216' extending within the hopper through the opening 218 to engage sides of cards within the hopper when said stack of cards is of sufficient height to reach same and thereby concurrently push this finger and the associated secondary finger 216'' on the spring arm 216 to the left, as viewed in Fig. 12, until the secondary finger is entirely free from contact with the side wall 202', thereby breaking electrical contact. However, when the stack of cards falls below the level of the lowermost section of the finger 216', it allows the latter to move to the right, as viewed in Fig. 12, until the finger 216'' engages the side wall 202', thereby completing an electric circuit to an audible signal 219 and/or visible signal 219', as diagrammatically illustrated by the wiring in Fig. 10 of the drawing.

Card controlling mechanism

A mechanism is provided for controlling or feeding the cards, namely, picking up one card 75

12

at a time from the hopper, transporting said one card from the hopper to an intermediate loading position below the grouping mechanism, and thereafter to an ejecting position, see Figs. 5 and 29. This mechanism in its present preferred form, includes a main slide 220 of generally H-shape, having sides 221 and 222, note Fig. 7, with a central and integral connecting web 223 adapted to pivotally support a pair of shafts 224 and 225 and to confine a pair of eccentrics 226 and 227 and gears 228 and 229 against lateral movement, as viewed in Figs. 5 and 7. Said pair of gears are meshed with a rack 230 to be rotated with the shaft and eccentrics thereon when the rack is reciprocated to the right and thence to the left, as viewed in Figs. 5 and 6. These eccentrics serve to provide a four point support for a main platen 231 and serve, as shown in Fig. 5, to move said platen from the lowermost position at the right hand side to the intermediate position at the left hand side and thence into a fully raised position shown centrally of Fig. 5. The position shown centrally of Fig. 5 is the showing of the machine in the particular cycle of operation of the shaft 72. The positions at the left and right of the slide 220 of Fig. 5 are also shown in full lines for clarity of the illustration, but these positions in reality would be dotted line positions of the parts. Side plates 232 secured to the main platen 231 as by screws and studs 233 and 234 respectively, and extending into channels 235 in the side walls 221 and 222, serve to prevent lateral or longitudinal misalignment of the platen relative to the main slide. This alignment is supplemented by studs 236 extended from main platen 231 downwardly through suitable apertures in the web 223 and screwed at the lower end into a pair of longitudinally extending plates 237, see Figs. 6 and 8 particularly. This latter pair of plates project from the web and underlie the eccentrics, thereby serving to pull the main platen downwardly when the high section of the eccentric is moved from the middle position to the right hand position shown in Fig. 5. The rack 230 is connected to a backing member 238 as by screws 239 and the latter in turn is connected to a pusher block 240 as by studs 241, the latter being accomplished first, this pusher block in turn having a pin connection 242 with a large drive lever 243 that has a pivoted and sliding connection 244 at its lower end to part of the main frame, as seen in Fig. 5. A block 245 is slidably mounted on the lever 243 with a rectangular slot, and the block 245 has a pivotal connection as at 246, on an eccentric plate 247, secured to the outer end of the main shaft 72. This drive lever is such that the pivot 246 on the eccentric plate through the sliding block 245 serves to oscillate the lever 243 to and from the dot and dash positions of the lever 243, as illustrated in Fig. 5.

Now it should be particularly noted that the present invention in its preferred form provides details in this mechanism for advantageously moving said platen into various vertical levels and to stop the main slide and platen in divers positions longitudinally of the rails while said lifting and lowering of the main platen occurs. This mechanism includes the provision of a key 248 (Fig. 7) preferably extending substantially throughout the full length of the rail 207' and backed by a plurality of springs 249, longitudinal shifting of the key 248 being prevented by a plurality of studs 250 having free axial sliding movement in the rail 207' and having a threaded connection in the key 248. A secondary function of

this key is to prevent the driving connection from lifting the main slide and its associated parts vertically within the rails and to maintain said main slide and associated parts in close sliding association with the under or supporting sections 251 and 251' of the rails 207 and 207'. Said springs 249 yieldingly push the key 248 against the main slide 220 and thereby maintain the latter in desired frictional association with the rail for purposes about to be described.

The rack 230 is maintained in proper horizontal association with gears 228 and 229 as by straps 252 and 252' joining the side walls and secured thereto, note Figs. 6 and 7. Thus the bottom wall of the backing member 238 is free to slide horizontally over the top faces of said straps 252 and 252', thereby maintaining rack teeth in proper pitch engagement with the gears.

Turning of the eccentrics 226 and 227 and concurrent lifting and lowering of the main platen 231 into divers predetermined positions and at predetermined points in the travel of the main slide 220 along the rails 207 and 207' is accomplished through the provision of a rear stud 253 and a front stud 254 on the rack 230 adapted to engage the cross-straps 252 and 252' respectively, and through the provision of a roller type detent 255 also adapted to engage the cross-straps 252 and 252'. Operation of these various elements is effected in cooperation with a spring pressing key 248 against the slide 220 in order to cause the side wall of the slide to have a continuous frictional sliding fit with side wall 222. The roller type detent 255 includes an inverted U-shaped yoke (Figs. 6, 7 and 8) having vertically sliding fit on a projection 256 at the rear end of the block 240 and retained upon the latter by the plate 257 and screws 258, note Fig. 7. This yoke is provided with integral projections 259 rotatably supporting a pair of rollers 260 which are held in place thereon by cotter pins. The yoke is normally urged upwardly by a spring 261 socketed in the projection and underlying the central section of the yoke sufficiently to bring the rollers 260 into contact with the bottom faces of the rails 262 and thereby permitting the top projection 263 on the yoke to engage against the rear face of the cross-strap 252 to push the entire slide and platen mechanism during a predetermined cycle of the machine. The release of this detent, namely, movement of the projection 263 below and out of registry with the cross-strap 252, is effected by rollers 260 engaging said rails 262, Figs. 5, 6 and 7, which serve to move the detent 255 downwardly until the projection 263 is entirely clear of the cross-strap 252 (as the slide is being moved to the left, as viewed in Fig. 6, and to the right of Fig. 5).

General operation of the card controlling mechanism is as follows:

During movement of the complete slide 220 and platen 231 from the ejecting position at the right hand side, Fig. 5, the stud 254 of the rack 230 engages the cross-strap 252', whereupon the arm 243 as it is rotated by the eccentric 247 serves to pull the slide and platen rearwardly. Throughout this travel from the ejecting position to the card pick up position, eccentrics 226 and 227, gears 228 and 229, and rack 230 are conditioned or positioned to maintain the platen in its lowermost position. However, after the slide has been moved to its extreme rearmost position by the stud 254 and arm 243 and the arm begins to move in a clockwise direction about its pivot, connection to block will cause the rack

to be moved slightly to the right (Fig. 5) while the slide is frictionally held by a spring pressed key 248 until the stud 254 is moved away from the cross-strap 252' and until the projection 263 of the detent 255 engages the cross-strap 252. During this slight movement of the rack, the gears 228 and 229 are rotated in a counter-clockwise direction approximately ninety degrees to move the lowest sections of the eccentrics out of registry with the under side of the main platen and to concurrently move the gradually increasing higher section of the eccentrics approximately half way around. The four eccentrics are each simultaneously moved an exact extent so that an even lifting of all four corners of the main platen is achieved. Further, a very accurate control of the lift of said eccentrics is achieved by reason of the abrupt and positive engagement of the projection 263 with the cross-strap 252. It should be noted that the slide and platen are stationary longitudinally of the rails while the gears and eccentrics are rotated ninety degrees and while the main platen is being lifted to the intermediate condition shown at the left of Fig. 5. When the platen 231 is in the lowermost condition (position at right in Fig. 5) platen 231 is entirely clear of the product being accumulated in the carding mechanism when it reaches this middle station, and entirely clear of the lowermost card in the hopper as it sweeps rearwardly under the hopper to the rearmost position. However, as the platen is lifted into the intermediate condition by the eccentrics, the top face of the platen comes into engagement with the lower face of the bottom card 182 in the hopper and pusher edges 231' on the platen are slightly to the rear of the rear edge of the card. Slots 264, note Fig. 12, in the top of the main platen 231 clear the three fingers 213, 213' and 213'' of the hopper when the main platen is lifted into the intermediate condition. After the detent 255 engages the cross-strap 252 and begins to move the main slide 220 and platen 231 to the right, as viewed in Fig. 5, pusher edges 231' push the lowermost card from the bottom of the stack of cards in the hopper through the port 215, note Fig. 10, toward the carding station. As the slide and platen move into the latter position, the rollers 260 ride downwardly on the rails 262 to pull the projection 263 out of registry with the cross-strap 252 and as the projection 263 becomes free of the cross-strap 252, spring pressed key 248 frictionally maintains main slide 220 and platen 231 in the longitudinal position of the rails while the arm 243 and block 240 steadily continue moving to the right, as viewed in Fig. 5, whereupon the associated rack 230 rotates the gears 228 and 229 and eccentrics 226 and 227 another ninety degrees in the counter-clockwise direction (Fig. 5) until the highest point of the eccentrics 226 and 227 are in engagement with the under side of the platen, thereby lifting the latter to its top or carding condition. When the rack, gears and eccentrics reach this position, under impetus of the eccentric 247 and arm 243, and while the slide 220 is stationary, the rear pin 253 is moved into engagement with the cross-strap 252 to thereafter positively drive the main slide 220 and platen 231 from the middle or carding condition farther to the right into the ejection condition. However, during this lifting action from the intermediate to the carding condition, the card is maintained flat upon the platen by a simple gravity weight, 265, note Figs. 14 and 16, which is maintained against longitudinal shifting by keys

266 at both sides thereof and limited in downward movement by a pin 267 underlying a ledge 268 thereon. Bottom faces of the stop plates 167, 167' and 167'' also rest upon the card to help maintain it flat upon the top face of the platen.

When the eccentric begins to swing the arm in a counter-clockwise direction at the ejecting station, the spring pressed key 248 maintains the slide 220 at the right hand or ejecting condition (Fig. 5) whereupon the arm 243 will pull the rack 230 to the left a considerable extent to fully lower the platen, and moving rear pin 253 away from the cross-strap 252 until the front pin 254 engages the cross-strap 252', whereupon the latter moves the main slide 220 and platen 231 15 conjointly below the hopper.

Modified slide control.

In Figs. 36 through 38 is diagrammatically illustrated a modified form of slide control, the slide being omitted for sake of clarity, but here reference to Fig. 5 of the drawing can be made. The modified slide control comprises the use of a series of spring pressed detents rather than the spring pressed key 248. Two detents 269 and 270 are shown, as slideably mounted in the rail 207', the detents being backed by springs 271 and 272 respectively. These two detents are adapted to hold the slide in the extreme end positions prior to shifting of the position of the platen in the slide. In the same respect, another detent 273, having a spring 274 is employed to check the slide in its central position when moving in the forward direction or in the direction of the delivery end. Note in Fig. 38 that the detents are arranged in different levels, compensating for the different levels of the platen in the slide at the three different stations. The bevelled surfaces at the inner ends of the detents facilitate outward movement thereof, as the slide moves back and forth in the frame.

Ejector

During ejector movement of the rack 239 relative to the main slide 220, gears 228 and 229 and eccentrics 226 and 227 are rotated in a clockwise direction at 180 degrees, whereupon the high parts of the eccentrics are moved downwardly into engagement with the plates 237, and low parts of the eccentrics are again brought into engagement with the underside of the main platen 231 to move the latter into its lowermost position. During this downward movement of the main platen, any card and any product on the card is deposited upon the top face of ejector fingers 275 of the ejector plate 276. The ejector plate 276 is pivoted on a stud or pin 277 and through a link connection 278 to a lever 279 having roller contact with a cam face 280 on the eccentric 247. Upward movement of the lever 279 about the pivot, and downward movement of the fingers 275 on the ejector plate 276 is limited by a stud 281 engaging a side of the lever 279, note Fig. 5. A spring 282 connected to the lever 279 and to projection 283 serves to normally maintain the ejector fingers 275 in the lowered full line position shown in Fig. 5, and concurrently maintain roller 284 in engagement with the eccentric 247. However, when the cam lobe 280 engages the roller 284, shortly after the platen 231 is moved into the lowermost position and after a card is thereby left on the ejector fingers 275 to move the lever downwardly and concurrently through the link to move the ejector fingers into the raised ejecting position shown in 75

dotted lines in Fig. 5, the card slides down these fingers and through the chute 285 into a suitable receptacle, not shown.

Band guide

In order to better locate the band 50 at a proper vertical height, and to prevent the same from being pushed back adversely relative to the rails 207 and 207', main platen 231 and relative to stop plates 167, 167' and 167'', male and female guide rollers 286 and 287 respectively, are provided at the outlet side of the carding apparatus. The female roller 287 is provided with a channel 288 adapted to receive the band, while the male roller is adapted to maintain the band within said channel, as may be seen best in Figs. 26 and 28. The female roller 287 is pivotally mounted on a stud at one end of a rack 289 having a slideable mounting in the channel 290 of a block 291. The male roller 286 is pivotally mounted on a stud connected with a yoke-shaped member 292 which supports another rack 293 slidable in another channel 294 of the block 291. These racks 289 and 293 are interconnected and operated by a pinion 295 rotatably mounted in the block 291. Thus as pinion 295 is rotated in a counterclockwise direction, as viewed in Fig. 26, the rack 289 and female roller 287 are moved downwardly, while the rack 293 and male roller 286 are simultaneously moved upwardly, whereupon said rollers are moved into the inoperative position shown in Fig. 28. Thereafter products carried by the band may be free to move therewith to the stripper mechanism of Fig. 4, hereinbefore described. The block 291 is vertically adjusted in a base plate 296 by clamp bolts engaging the plate and operated in elongated slots 297 in the block, as noted in Fig. 26. This controls vertical positioning of the rollers with respect to the band 50. The base plate 296 is adjusted laterally by bolts 298 engaging the rail 207' and operating in elongated apertures 299, also as seen in Fig. 26. On the bolts 298 are spacing washers 300, note Fig. 27, for spacing the base plate from the rail. The pinion 295 has an extending shaft end 301 having a cross-bar 302 for manually rotating the pinion to move the rollers toward and from each other. This same result can be accomplished by a lever 303, pivoted as seen at 304, and having a pin end 305 secured to the rack 289 and operating in an elongated slot 306 in the base plate 296. In addition to spacing the rollers, as seen in Fig. 28 to clear the products on the band, the same mechanism for separating the rollers 286 and 287 is also utilized to raise the stop plates 167, 167' and 167''. This result is accomplished by another rack 307 supported upon the yoke 292, note Fig. 26, and meshing with a pinion 308 at the outer end of the cam shaft 198. It will thus be apparent that when the rack 293 is raised to raise the roller 286, the rack 307 rotates the pinion 308 to move the cams 197 into the raised position shown in Fig. 28, thus raising all of said stop plates.

In the operation of the machine, it will be understood that the products or wire-forms 118 are first produced at the forming station 57 and applied to the band in a definite spaced relationship one with respect to the other, which is controlled by the ratio of feed of the band through the forming machine. The products or workpieces 118 are then fed through the tempering or burning off oven 58, then through the guide rollers 59, then beneath the sprayer 60 for the application 70 of the coating material to be applied, then be-

neath the air spout 61 for the removal of surplus coating material, and thereafter through the baking and drying oven 62.

The treated, coated and dried products or workpieces now enter the packaging unit 63, in which unit the products or workpieces are counted, segregated, and staggered in predetermined groups, and then mounted in said staggered relationship on a packaging card, which is then delivered from the machine. Here it might be said, that should the unit 63 not be put into operation, or should the parts of the unit be set in condition to clear the workpieces 118 on the band 50, as previously described, these workpieces would extend to the stripper mechanism involving the rollers 66 and be removed from the band. However, when the unit 63 is in operation, and it is desired to automatically count, disperse and card the products or workpieces, the following operations are observed.

The clutch lever 92 is operated to move the plunger 91 into the lowered position of Fig. 23, whereupon the clutch 84 rotates the main shaft 72 of the carding unit in unison with and predetermined ratio to the shaft 71 and the shaft of the forming machine, the latter having been rendered rotatable and operative by dog tooth clutch 77. Substantially concurrently with operation of the clutch, lever 303 is also operated to move the band guide comprising the rollers 286 and 287, Figs. 26 through 28, into the closed or operative position of Fig. 26, and to concurrently move the cam 197 into the lowered inoperative position so that stop plates 167, 167' and 167'' may be conditioned by cams 169, 169' and 169'' respectively. Upon rotation of said main shaft 72 of the packaging unit 63, small groups of product of predetermined quantity are made up by the counting mechanism, Figs. 19 through 21 and 29, per one form of the invention. If it is desired to stagger groups of such counted and grouped product transversely relative to the carrier band 50, staggering mechanism of Figs. 19, 21 and 22 is included in the apparatus and operated in the manner hereinbefore described. Subsequently to the counting and staggering of the groups of product, the latter are moved by the band 50 into the carding unit, Figs. 13 through 18, where they are intercepted by stop plates 167, 167' and 167'', the latter serving to close the groups relative to each other longitudinally relative to the band travel. Concurrently with the counting, staggering and transporting of said groups of product, the lever 243 moves the slide 240 and the platen 231 under the hopper 201, lifts the platen into the intermediate position where it picks up one card and transports it on the intermediate plane to a position underlying the groups of pins being collected against the three stop plates. At this point and substantially concurrently with collection of three groups of product against the three stop plates, the platen 231 is moved into the uppermost position, pressing the fingers 192, 192' and 192''. The fingers are then moved upon the free or open ends of the groups of product and the staggering and/or backing fingers 180, 180' and 180'' are moved over and in back of the groups of product, note Fig. 16. Thereafter the slide 240 and platen 231 are moved to the right from the central position of Fig. 5. In this operation, ends 118' at one side of the product are snapped through apertures 182' in the card 182, see Fig. 16, while the projection 231' on the platen pushes the card forwardly with respect to the band 50 until the aper-

ture reaches the inside section of the eye of the product to accurately load the several groups of product in staggered relation upon a single card. Immediately thereafter the pressing fingers and the staggering and/or backing fingers are lifted to the inoperative position to permit movement of the groups of product together with the card from the intermediate loading position to the right hand unloading or ejecting position of Fig. 5. After the product 118 is entirely clear of the band (final removal of the product from the band being effected by the card), stop plates 167, 167' and 167'' are raised to the top inoperative position by the cams 169, 169' and 169'', carried by the shaft 170. When the slide 240 reaches the right hand position of Fig. 5, the platen 231 is lowered in the manner hereinbefore described, to deposit the loaded card or product holder upon the ejector fingers 275, whereupon the latter serve to eject the packaged product from the machine as by cam lobe 280 operating the linkage to the ejector plate, as shown in Fig. 5. Successive groups of product and units of packaged product are made by continuous cycles of the machine as just described. The staggering mechanism of Figs. 19, 21 and 22 may be eliminated and the staggering effected entirely by fingers 141, 141' and 141'', but a lighter load is imposed upon the latter by making use thereof.

Operation of the packaging unit 63 may be effected with the modified mechanism of Figs. 30 through 35 substantially in the same manner but with the added advantage of effecting a closed longitudinal relationship of the groups of product on the band prior to the groups coming into engagement with stop plates 167, 167' and 167''. Variations and modifications may be made within the scope of the invention and portions of the invention may be used without others.

Considering Fig. 29 of the drawing, it will be apparent that as the band 50 approaches the unit 63, the products or workpieces 118 are in wide spaced relationship to each other, substantially as illustrated at the lower part of said figure. First one group of a predetermined number of the products is formed, then a second group and then a third group, and these groups are arranged in the staggered relationship substantially as shown at 118a, 118b and 118c of said figure. In this relationship, the grouped products are simultaneously applied to the mounting card 182, being arranged on the card substantially in the staggered relationship assumed on the band 50. Any desired number of products can be arranged in each group and the staggered relationship varied by constructing and operating the mechanism of the machine accordingly. The staggered relationship of the holes 182' of the cards 182 is shown at the right of Fig. 29, where the cards are disposed in the hopper 201.

Briefly stated, in the complete operation of the machine, the endless band 50 travels continuously, the workpieces or products are formed and applied to the band, run through the processing stages 58, 60, 61 and 62, and then through the grouping, staggering and carding unit 63, from which unit the carded products are automatically discharged and this operation is continuous as long as the machine is in operation. In some uses of the apparatus, the products may be formed and applied to the conveyor band 50 in any desired manner and then passed through the counting, grouping and carding unit, generally referred to as the packaging unit. Here

again it is to be kept in mind that when processing is required, the nature of this processing may be varied to suit the product being formed and packaged.

For purposes of description, the band upon which the products or workpieces are formed and mounted, may be regarded as a carrier or mounting member utilized in feeding the products or workpieces to their respective stations. For example, the heater station 58, spraying station 60, blower station 61, baking or drying station 62, counting, grouping and packaging station 63, and in some instances, to the stripper station 64. Also it may be said that at the station 63 are three auxiliary stations comprising the hopper or card delivery station, the mounting station, where the products or workpieces are mounted on the card, and the ejector or delivery station from which the mounted products are discharged into a suitable receiver.

Having fully described my invention, what I claim as new and desire to secure by Letters Patent is:

1. In apparatus for automatically forming, processing and mounting wire forms, a constantly moving carrier on which the formed and processed products are arranged in predetermined spaced relationship to each other, a mounting unit into and through which the carrier is adapted to pass, means in said unit for gathering the products on the moving carrier in groups, each group containing a predetermined number of products, means in said unit for delivering a mounting member, means for feeding the mounting member relatively to the path of movement of the carrier to automatically remove the grouped products from the carrier and position the same on said mounting, and means to then eject the mounting member with the products thereon from said unit.

2. In apparatus for automatically forming, processing and mounting wire form products, a constantly moving carrier on which the formed and processed products are arranged in predetermined spaced relationship to each other, a mounting unit into and through which the carrier is adapted to pass, means in said unit for gathering the products on the moving carrier in groups, each group containing a predetermined number of products, means for staggering the groups of products one with respect to the other on said moving carrier, means for delivering and moving a mounting member having staggered openings therein relatively to the carrier to pick-up and remove the staggered groups of product from the carrier and arrange the same in the staggered openings of the mounting member, and means to then discharge the mounting member with the staggered grouped products thereon from said unit.

3. In apparatus of the class described employing a continuously moving product carrier on which individual products are arranged in spaced relationship to each other longitudinally of the carrier, a machine through which the carrier is automatically fed, said machine having means for grouping the products on the moving carrier, means for delivering a mounting member into position transversely with respect to the movement of said carrier and to feed said member with respect to the carrier in removing the grouped products from the carrier and depositing the same upon said member, and means for discharging the member with the products thereon from said machine.

4. In apparatus of the class described employing a continuously moving product carrier on which individual products are arranged in spaced relationship to each other longitudinally of the carrier, a machine through which the carrier is automatically fed, said machine having means for grouping the products on the moving carrier, means for delivering a mounting member into position transversely with respect to the movement of said carrier and to feed said member with respect to the carrier in removing the grouped products from the carrier and depositing the same upon said member, means for discharging the member with the products thereon from said machine, the means for delivering and moving said mounting member comprising a platen, and means for moving and supporting the platen in different vertical positions in the complete cycle of delivery, feed and discharge of said mounting member.

5. In apparatus of the class described employing a continuously moving product carrier on which individual products are arranged in spaced relationship to each other longitudinally of the carrier, a machine through which the carrier is automatically fed, said machine having means for grouping the products on the moving carrier, means for delivering a mounting member into position transversely with respect to the movement of said carrier and to feed said member with respect to the carrier in removing the grouped products from the carrier and depositing the same upon said member, means for discharging the member with the products thereon from said machine, the means for delivering and moving said mounting member comprising a platen, means for moving and supporting the platen in different vertical positions in the complete cycle of delivery, feed and discharge of said mounting member, and said last named means comprising a plurality of platen supporting and operating eccentrics.

6. In apparatus of the class described employing a product carrier on which individual products are arranged in spaced relationship to each other longitudinally of the carrier, a machine through which the carrier is automatically fed, said machine having means for grouping the products on the carrier, means for delivering a mounting member into position transversely with respect to the movement of said carrier and to feed said member with respect to the carrier in removing the grouped products from the carrier and depositing the same upon said member, means for discharging the member with the products thereon from said machine, the means for delivering and moving said mounting member comprising a platen, means for moving and supporting the platen in different vertical positions in the complete cycle of delivery, feed and discharge of said mounting member, said last named means comprising a plurality of platen supporting and operating eccentrics, and means comprising gears on the shafts of the eccentrics and a rack engaging said gears for moving the eccentrics into different positions.

7. In apparatus of the class described employing a continuously moving product carrier on which individual products are arranged in spaced relationship to each other longitudinally of the moving carrier, means engaging the products on the moving carrier to group a predetermined number of said products on the moving carrier, and means in spaced relation to said grouping means for moving a packaging member trans-

versely of said carrier to thereby deposit the grouped products on said member in removing the same from said carrier.

8. In apparatus of the class described employing a product carrier on which individual products are arranged in spaced relationship to each other longitudinally of the carrier, means engaging the products on the carrier to group a predetermined number of said products on the carrier, means operatively engaging grouped products on said carrier for arranging a predetermined number of product groups in predetermined staggered relationship to each other on said carrier, and means spaced with respect to said last named means for supporting the grouped products in said staggered relationship and to otherwise support said products preparatory to transfer onto a mounting member.

9. In apparatus of the class described employing a product carrier on which individual products are arranged in spaced relationship to each other longitudinally of the carrier, means engaging the products on the carrier to group a predetermined number of said products on the carrier, means operatively engaging grouped products on said carrier for arranging a predetermined number of product groups in predetermined staggered relationship to each other on said carrier, means spaced with respect to said last named means for supporting the grouped products in said staggered relationship and to otherwise support said products preparatory to transfer onto a mounting member, and means for delivering and moving a mounting member transversely with respect to said supported, staggered groups of products in transferring the products from said carrier to said member and for the ejection of said member and products thereon from the machine.

10. In apparatus of the class described employing a product carrier on which individual products are arranged in spaced relationship to each other longitudinally of the carrier, means engaging the products on the carrier to group a predetermined number of said products on the carrier, means operatively engaging grouped products on said carrier for arranging a predetermined number of product groups in predetermined staggered relationship to each other on said carrier, means spaced with respect to said last named means for supporting the grouped products in said staggered relationship and to otherwise support said products preparatory to transfer onto a mounting member, means for delivering and moving a mounting member transversely with respect to said supported, staggered groups of products in transferring the products from said carrier to said member and for the ejection of said member and products thereon from the machine, said last named means comprising a transversely aligned mounting member feed station, a product intercepting station and an ejection station, and a slide for moving the mounting member from the first to the second and third named stations.

11. In apparatus of the class described employing a product carrier on which individual products are arranged in spaced relationship to each other longitudinally of the carrier, means engaging the products on the carrier to group a predetermined number of said products on the carrier, means operatively engaging grouped products on said carrier for arranging a predetermined number of product groups in predetermined staggered relationship to each other on

said carrier, means spaced with respect to said last named means for supporting the grouped products in said staggered relationship and to otherwise support said products preparatory to transfer onto a mounting member, means for delivering and moving a mounting member transversely with respect to said supported, staggered groups of products in transferring the products from said carrier to said member and for the ejection of said member and products thereon from the machine, said last named means comprising a transversely aligned mounting member feed station, a product intercepting station and an ejection station, a slide for moving the mounting member from the first to the second and third named stations, and said slide including a mounting member supporting a platen movable into different vertical positions at said respective stations.

12. In apparatus of the class described employing a product carrier on which individual products are arranged in spaced relationship to each other longitudinally of the carrier, means engaging the products on the carrier to group a predetermined number of said products on the carrier, means operatively engaging grouped products on said carrier for arranging a predetermined number of product groups in predetermined staggered relationship to each other on said carrier, means spaced with respect to said last named means for supporting the grouped products in said staggered relationship and to otherwise support said products preparatory to transfer onto a mounting member, means for delivering and moving a mounting member transversely with respect to said supported, staggered groups of products in transferring the products from said carrier to said member and for the ejection of said member and products thereon from the machine, said last named means comprising a transversely aligned mounting member feed station, a product intercepting station and an ejection station, a slide for moving the mounting member from the first to the second and third named stations, said slide including a mounting member supporting a platen movable into different vertical positions at said respective stations, and means at each station for momentarily supporting the slide against movement at each station in shifting the platen into a different vertical position at said stations.

13. In a machine employing a mounting member supply station, a station for assemblage of products on a mounting member and a station for ejecting said member with the products thereon from the machine, a carriage unit movable relatively to said stations, said unit comprising a slide, means for automatically moving the slide in a predetermined plane back and forth with respect to all of said stations, said slide including a platen movable into different vertical positions in the slide, means comprising a pair of gears rotatably mounted in said slide and a rack bar slidably engaging said slide and operatively engaging said gears for controlling vertical positions of the platen in said slide at the different stations, and means supporting the slide against movement at each station in movement of said rack relatively to the slide at each station in shifting the platen into different positions.

14. In a machine employing a mounting member supply station, a station for assemblage of products on a mounting member and a station for ejecting said member with the products thereon from the machine, a carriage unit movable

relatively to said stations, said unit comprising a slide, means for automatically moving the slide in a predetermined plane back and forth with respect to all of said stations, said slide including a platen movable into different vertical positions in the slide, means comprising a pair of gears rotatably mounted in said slide and a rack bar slidably engaging said slide and operatively engaging said gears for controlling vertical positions of the platen in said slide at the different stations, means supporting the slide against movement at each station in movement of said rack relatively to the slide at each station in shifting the platen into different positions, and means checking movement of the rack in each direction relatively to said slide.

15. In a machine employing a mounting member supply station, a station for assemblage of products on a mounting member and a station for ejecting said member with the products thereon from the machine, a carriage unit movable relatively to said stations, said unit comprising a slide, means for automatically moving the slide in a predetermined plane back and forth with respect to all of said stations, said slide including a platen movable into different vertical positions in the slide, means comprising a pair of gears rotatably mounted in said slide and a rack bar slidably engaging said slide and operatively engaging said gears for controlling vertical positions of the platen in said slide at the different stations, means supporting the slide against movement at each station in movement of said rack relatively to the slide at each station in shifting the platen into different positions, and means on the platen for picking-up a single mounting member at the first station and for feeding the member to each of the other two stations.

16. In a machine employing a mounting member supply station, a station for assemblage of products on a mounting member and a station for ejecting said member with the products thereon from the machine, a carriage unit movable relatively to said stations, said unit comprising a slide, means for automatically moving the slide in a predetermined plane back and forth with respect to all of said stations, said slide including a platen movable into different vertical positions in the slide, means comprising a pair of gears and a rack bar slidably engaging said slide and operatively engaging said gears for controlling vertical positions of the platen in said slide at the different stations, means supporting the slide against movement at each station in movement of said rack relatively to the slide at each station in shifting the platen into different positions, means on the platen for picking-up a single mounting member at the first station and for feeding the member to each of the other two stations, said mounting member having spaced product receiving apertures therein, and means at the second station for supporting the products in position to pass through the apertures of said member in the feed of said member by the platen transversely with respect to said second station.

17. In a machine employing a mounting member supply station, a station for assemblage of products on a mounting member and a station for ejecting said member with the products thereon from the machine, a carriage unit movable relatively to said stations, said unit comprising a slide, means for automatically moving the slide in a predetermined plane back and

forth with respect to all of said stations, said slide including a platen movable into different vertical positions in the slide, means comprising a pair of gears and a rack bar slidably engaging said slide and operatively engaging said gears for controlling vertical positions of the platen in said slide at the different stations, means supporting the slide against movement at each station in movement of said rack relatively to the slide at each station in shifting the platen into different positions, means on the platen for picking-up a single mounting member at the first station and for feeding the member to each of the other two stations, said mounting member having spaced product receiving apertures therein, means at the second station for supporting the products in position to pass through the apertures of said member in the feed of said member by the platen transversely with respect to said second station, the apertures of said mounting member being staggered, and said last named means including means for supporting a staggered arrangement of products for simultaneous feed to the staggered apertures of said mounting member.

18. In a machine for automatically carding products arranged in spaced relationship to each other on a carrier, means for feeding an apertured card transversely with respect to the carrier with the apertures of the card in alignment with products supported on said carrier, means backing and supporting the products to feed the same into the apertures of the card as the card is fed transversely of the carrier and moved into predetermined position on the card and then to release said products in ejection of the card with the products thereon from the machine, means adjacent said last named means for maintaining products in spaced relationship to each other longitudinally with respect to said carrier during the carding operation, and manually actuated means for moving the last named means and said backing means out of operative engagement with the products in providing free passage of the products, on said carrier, with respect to both of said means.

19. In a machine for automatically packaging products arranged in spaced relationship to each other on a carrier movable through a packaging station, a product alining station for alining products on the carrier in staggered relationship to each other, said station comprising relatively movable alining jaws arranged at opposed sides of and movable toward and from said carrier and products disposed thereon, a cam disc comprising pairs of opposed cams adjustably supported on the disc, and a pair of levers operatively coupled with said jaws and engaging the cams of said disc to intermittently move successive products on the carrier transversely with respect thereto in disposing a predetermined series of products in staggered relationship to each other in each cycle of operation of the machine.

20. In a machine for automatically packaging products arranged in spaced relationship to each other on a carrier movable through a packaging station, a product alining station for alining products on the carrier in staggered relationship to each other, said station comprising relatively movable alining jaws arranged at opposed sides of and movable toward and from said carrier and products disposed thereon, a cam disc comprising pairs of opposed cams adjustably supported on the disc, a pair of levers operatively coupled with said jaws and engaging the cams

of said disc to intermittently move successive products on the carrier transversely with respect thereto in disposing a predetermined series of products in staggered relationship to each other in each cycle of operation of the machine, and said jaws including means adjusting relative positions thereof.

21. In a machine for automatically carding products arranged in spaced relationship to each other on a carrier, means for feeding an apertured card transversely with respect to the carrier with the apertures of the card in alinement with products supported on said carrier, means backing and supporting the products to feed the same into the apertures of the card as the card is fed transversely of the carrier and moved into predetermined position on the card and then to release said products in ejection of the card with the products thereon from the machine, means adjacent said last named means for maintaining products in spaced relationship to each other longitudinally with respect to said carrier during the carding operation, means engaging the carrier adjacent the carding station for supporting and guiding the carrier in predetermined position, and manually actuated means for moving said last named means, the product holding means and the product backing means into inoperative positions with respect to the products on the carrier in providing free movement of uncarded products through said respective means.

WILLIAM F. FEYRER.
